United States Patent Office

Des. 199,685
Patented Dec. 1, 1964

199,685

PLATE OR SIMILAR ARTICLE

Tsugitaka Sugiyama, 170 Nagaide, Inazawa, Japan

Filed Jan. 7, 1964, Ser. No. 78,112

Term of patent 3½ years

(Cl. D44—15)

The figure is a plan view of a plate or similar article showing my new design, a portion of the design being shown between dotted lines and a repeat portion being shown between dot-and-dash lines.

The plate is of a conventional configuration when viewed from the side and bottom thereof.

I claim:

The ornamental design for a plate or similar article, substantially as shown and described.
